PIPE CLEANING OVEN

Forrest A. Smith, Fort Worth, Tex.

Application March 23, 1945, Serial No. 584,279

7 Claims. (Cl. 263—2)

1

This invention relates to a pipe cleaning oven.

An object of the invention is to provide pipe cleaning equipment of the character described specially designed for use in cleaning pipe lines that have been previously buried in the earth and which must be reconditioned to arrest corrosion.

As is well known it is necessary to recondition pipe lines at intervals. In order to do this the line is raised above the ground surface and is first cleaned mechanically by a conventional type of pipe cleaner which removes the earth, scales and other foreign matter from the surface of the pipe. However, this mechanical operation leaves a certain amount of corrosion, particularly when the surface of the pipe is pitted. It is another object of the present invention to provide an oven which surrounds, and is movable along, the pipe line and by means of which the surface of the pipe may be heated so as to destroy all remaining corrosion and foreign matter that may be on the surface of the pipe so that the pipe will be perfectly clean and free of all corrosive substances. The pipe is then coated with a suitable painting material and wrapped and then again buried in the earth.

Another object of the invention is to provide an oven of the character described which will conserve the heat so that it will be applied to the pipe, which is readily movable along the pipe and which may be easily applied to or removed from the pipe.

With the above and other objects in view the invention has particular relation to certain novel features of construction, operation and arrangement of parts, an example of which is given in this specification and illustrated in the accompanying drawings, wherein:

Figure 1 shows a side view of the equipment mounted on a raised pipe line.

Figure 2 shows a perspective view thereof.

Figure 3 shows a plan view.

Figure 4 shows an end view showing the oven partly opened and partly in section.

Referring now more particularly to the drawings wherein like numerals of reference designate similar parts in each of the figures, the numeral 1 designates a longitudinal bar having the downwardly diverging front and rear legs 2, 2 and 3, 3 whose upper ends are welded or otherwise secured to the bar 1.

The lower ends of these legs are forwardly and rearwardly turned, respectively, and are provided with the front and rear bearings 4, 4 and 5, 5, respectively, in which the front and rear axles 6 and 7 are mounted to rotate. Fixed on these axles are the front wheels 8, 8 and the rear wheels

2

9, 9. These wheels are beveled as shown to conform to the contour of the pipe along which they travel.

An arch shaped carriage is thus formed from which the oven proper is swung. This oven is formed of two half round sections 10, 10 which are hinged to the bar 1 of the framework by means of hinges 11 so that the sections of the oven may be opened and closed.

As will be noted from an inspection of Figures 1 and 3 the ends of the oven are of frusto-conical shape, that is they taper outwardly and terminate in the sectional collars as 12 which surround the pipe rather snugly but with sufficient clearance to allow the oven to move along the pipe without interference. The sections of the oven may be latched around the pipe by means of a latch 13.

Fastened to the sides of the oven, one on each section 10 thereof, are the hoods 14 through which the nozzle pipes 15, 15 extend into the oven. These hoods are perforated as shown to admit auxiliary air into the oven on each side.

Fastened to the rear end of the frame of the carriage there is a transverse sleeve 16 for the reception of a transverse rod 17. The oven may be propelled along the pipe line by workmen, one on each side, using the rod 17 and by the use of said rod the oven may be also maintained stabilized on the pipe line. Rearwardly of the oven carriage there is a dolly comprising the platform 18 whose rear end is supported on the pipe by the carrier wheels 19 and whose forward end is coupled to the rear end of the oven frame.

Mounted on the dolly platform there is a fuel tank 20 provided to contain kerosene or other selected fuel.

It is contemplated that an air compressor will move along the line mounted on a suitable vehicle. It is, of course, obvious that the dolly platform 18 could be extended and the compressor mounted on it.

Leading from the compressor there is a hose 21 which is connected into the tank 20 so as to place the liquid in the tank under compression. An outlet pipe 22 is anchored to the top of the tank 20 and extends down into the tank beneath the level of the liquid therein as shown in dotted lines in Figure 1. Connected to the upper end of the discharge pipe 22 are the hose 23, 23 which lead to the nozzles 24, 24 which are anchored to, and project into, the outer ends of the nozzle pipes 15, 15 and which are controlled by suitable hand operated needle valves 25, 25; also connected with the pressure line 21 there are the hose 26, 26 which are connected into the outer ends of the

nozzle pipes 15 so as to discharge air under compression around the nozzles 24, 24. The fuel will thus be forced under pressure through the nozzles 24 and the nozzle pipes 15 and will be broken up and atomized by the air forced through the hose 26, 28 and will enter the oven in combustible vapor form which, when ignited, will create a flame within the oven all around the pipe to be cleaned so that all foreign matter and corrosive material on the pipe will be destroyed as the oven moves along the pipe.

It is contemplated that the oven carriage may be motor driven. For that purpose a motor 21 may be mounted on the oven frame. The shaft of this motor may be provided with a sprocket wheel 28 which is aligned with a corresponding sprocket wheel 29 fixed on the axle 6 and a sprocket chain operating over said sprocket wheel will transmit rotation from the former to the latter and to the carrier wheels 8, 8.

If this motor is employed to move the oven along the pipe the rod 17 will be used only for the purpose of stabilizing the machine on the pipe.

The oven sections should be lined with asbestos 30 as is shown in Figure 4.

The drawings and description are illustrative merely while the broad principle of the invention will be defined by the appended claims.

What I claim is:

1. An oven for applying heat to the outer surface of pipe and shaped to fit around the pipe to form an enclosed chamber about the pipe, means for supplying a combustible mixture into said chamber and carriers associated with the oven and arranged to move in contact with the pipe for relatively moving the oven longitudinally with respect to the pipe.

2. An oven for applying heat to the outer surface of a pipe and formed of sections arranged to be closed around the pipe and form an enclosed chamber about the pipe, means for supplying a combustible mixture into said chamber and means for relatively moving the oven longitudinally with respect to the pipe.

3. A pipe cleaner comprising a carriage, adapted to move along the pipe to be cleaned, oven sections hinged thereto and depending therefrom and shaped to close about the pipe and form a chamber around the pipe and means for supplying a combustible mixture into said chamber.

4. A pipe cleaner comprising a carriage, adapted to move along the pipe to be cleaned, oven sections hinged thereto and depending therefrom and shaped to close about the pipe and form a chamber around the pipe, means for supplying a combustible mixture into said chamber and means for moving the carriage and oven along the pipe.

5. A pipe cleaner comprising a carriage, adapted to move along the pipe to be cleaned, an oven carried by the carriage and shaped to surround a pipe and form an enclosed chamber about the pipe and means for supplying a combustible mixture into said chamber.

6. A pipe cleaner comprising a carriage, an oven mounted on the carriage and shaped to surround a pipe and to form an enclosed chamber about the pipe, nozzle pipes entering the chamber, means for supplying a combustible mixture through said nozzle pipes into the chamber.

7. A pipe cleaner comprising a carriage adapted to move along the pipe to be cleaned, an oven supported by the carriage and shaped to surround the pipe and to form an enclosed chamber about the pipe, hoods on the oven provided with perforations, nozzle pipes extended through the hoods into the chamber and means for supplying a combustible mixture through said nozzle pipes into the chamber.

FORREST A. SMITH.
